METHOD FOR PRODUCING LATHER BY
CENTRIFUGAL ACTION OF FLUID
OVER A SOAP CAKE SURFACE

Gordon C. Johnson and Alden O. Johnson, Minneapolis, Minn., assignors to John Oster Manufacturing Company, Racine, Wis., a corporation of Wisconsin

Application March 14, 1947, Serial No. 734,598

3 Claims. (Cl. 299—83)

1

This invention relates to mechanism and method for producing soap lather for shaving or washing purposes, and the primary object is to provide a lather creating dispenser which carries out the method or process quickly and efficiently to the end that a warm, rich lather will be made available for the uses indicated.

More particularly the method includes the spinning of a cake of soap and the application of water axially to the center of its exposed surface whereby centrifugal action will cause such water to remove, from the soap cake surface, sufficient amounts of the soap to produce the desired lather, and to then agitate the same to thereby complete the lather or foaming operation.

The present invention embodies many of the features and mechanical details disclosed in our co-pending application Serial No. 587,692, filed April 11, 1945, for Lather Machine, and in which a weighted scraper is placed upon the soap cake to mechanically scrape the soap from the cake. For that reason reference is made to that earlier application for such structural features as are not herein set forth or disclosed in detail.

The present invention contemplates little more, from a structural standpoint, than the removal of the weighted scraper, 60, as identified and employed in the earlier application. And while our earlier structure and theory of operation is efficient, and the scraper feature may well continue to be used, we have found that with the removal of the scraper and with suitable control adjustments a substantial different and more efficient effect is produced. Not only is the soap film removed by a different process or action than previously anticipated, but we have also eliminated objectionable gyratory vibrations which frequently resulted from eccentric displacement of the loose scraper in the soap cup.

In the accompanying drawings, which illustrate the present structure and the process of forming lather thereby,

Fig. 1 is a sectional elevation through the machine taken diametrically through the lather chamber, and substantially in the plane represented by Fig. 1 in the drawings of our co-pending application Serial No. 587,692.

Fig. 2 is a top or plan view of the machine with fractional parts broken away for purpose of illustration.

Fig. 3 is a sectional elevation on the irregular line 3—3 in Fig. 2.

Referring to the drawings more in detail, and by reference characters, A designates the main block or body of the machine, preferably formed of cast metal or plastic material, and includes a shallow integrally formed base B. A removable cover C fits snugly and neatly upon the upper

end of the body A and is releasably secured by a single knurled nut or thumb screw 4.

The body block A is provided with chambers D, E, F, and G, chamber D being a compartment for an electric motor 5, chamber E being the lather chamber, chamber F being a water reservoir, and chamber G being an enlargement in a water heating and circulating passageway.

Chambers D and G open downwardly and are normally closed by a cover plate 6 concealed within base B and releasably secured by screws 7. The chambers E and F project upwardly into the cover C and are of course normally closed thereby. This cover has a centering flange 8 fitting within the chamber E to accurately locate the cover, and which also functions in the lathering process as will presently be noted.

The electric motor 5 has a double ended shaft 10, the upper end of which projects axially into the lather chamber E while the lower end extends downwardly into the cover plate 6 to operate a centrifugally acting water pump 11. This pump is connected to receive water from the reservoir F and force it through a duct 12 into the chamber G, wherein it is heated by an electric heating element 13, after which it is forced up through passageways 14 and 15 to a nozzle 16 arranged axially of and directed downwardly into the chamber E. This nozzle is provided with a valve 17 by which the flow of water delivered by the nozzle may be accurately adjusted. In this manner the motor 5 is operative, when energized, to deliver a constant supply of heated water from the reservoir F to the nozzle 16, while also and simultaneously actuating the lather producing device, as will now be set forth.

A soap support or holder in the general form of a cup 18 is rigidly but releasably secured upon the upper end of the shaft 10, by a nut 19, and this cup is spaced from the inner walls of the chamber E so that it will be free to spin when rotated by the motor shaft. While this cup may be modified in several particulars, as shown in our co-pending application Serial No. 587,692, the design here shown comprises a substantially flat bottom from which upwardly extends a cylindrical wall, open at its upper end and adapted to receive and support a circular soap mass or cake 20. The exterior surface of the cup wall is provided with vertical flutes or corrugations 21 while the inwardly opposed wall of the chamber is provided with somewhat similar corrugations 22 which cooperate with the corrugations 21, when the cup is spun, to churn into a lather the soap solution so produced.

The device operates to carry out the method of the present invention as follows: With the motor 5 energized the shaft 10 operates to rapidly rotate the cup 18 with its supported soap mass 20 while also functioning to actuate the pump 10. The

motor switch (not shown) may also control the circuit to the heating element 13, but this may be separately switch controlled if so desired. In any event, with the pump rotating and the chamber G heated, water is circulated from the reservoir F to the nozzle 16 from which it descends at proper temperature, and in such desired volume as may be determined by adjustment of the valve 17.

As the restricted stream of water leaves the nozzle 16 it descends into contact with the rapidly rotating soap body at a point coaxially thereof, and, since the entire upper surface of the soap mass is entirely exposed, this water, under centrifugal action, is dispersed radially in all directions, in a thin sheet or film. It is found, by extensive experiment and testing, that the movement of this film of water outwardly over the soap surface sufficiently dissolves the soap to remove portions thereof, without mechanical assistance, and in sufficient quantity to produce a rich soap solution. The required aeration is produced by a duct 23, through which air is admitted under atmospheric pressure.

A primary lather is thus produced from the soap solution as the same is agitated by the inner surface of the rotating cup wall, and this primary lather builds up in the chamber space above the soap surface until that space is filled, after which the lather escapes over the rim of the cup and downwardly into the peripheral space between the cup wall and the chamber wall. Here the opposed and relatively moving corrugations or ribs 21 and 22 again engage the lather to violently churn and agitate the same until a final form of lather with most desired consistency and quality is produced. This churning action also of course increases the volume of lather which, with the added pressure produced by the initial or inner cup process, causes the resultant product to feed in a full and constant flow out through the only escape port, which is a nozzle 24, from which it is conveniently caught in the hand, on the brush, or in some receptacle, all ready for use.

Reference has previously been made to the cover flange 8 and it will be seen from Figs. 1 and 3, that its lower edge projects inwardly toward the cup 18. It will also be noted that the upper edge of the cup is provided with an out-turned flange 25, offset upwardly with respect to the lower edge part of flange 8. In this way the passage of the lather from within the cup to the corrugated beaters (21-22) is somewhat lengthened and constricted, and this is found to improve the quality of the lather.

The centrifugal action which produces the thin film of water over the entire exposed upper surface of the soap body is indicated particularly in Figs. 1 and 3, while in Fig. 2, a part of the lather mass is shown broken away to expose the soap body itself and in which is illustrated by radial lines how the water action is effective to cut away surface indentations in the soap.

Having now fully disclosed our improved method and a preferred mechanism by which the same may be practiced, what we claim is:

1. The method of producing lather which is characterized by the steps of: rotating a cake of soap having an exposed face which is substantially perpendicular to the axis of rotation; admitting air directly to the exposed face of the soap cake; forcibly injecting a stream of liquid onto said face of the soap substantially coaxially therewith to thus enable centrifugal force due to

rotation of the soap to move the liquid radially outwardly across said face of the soap in a thin film so that quantities of soap are dissolved in the liquid to form a soap solution; and abruptly deflecting the outwardly moving film of liquid as it leaves the soap to cause at least a portion thereof to be returned across the radially outer portion of said face of the soap to increase the concentration of the soap solution and to entrain air therein so as to initiate the formation of lather.

2. The method of producing lather which comprises the steps of: rapidly rotating a cake of soap having an exposed surface normal to its axis; admitting air directly to the exposed surface of the soap cake; applying a small quantity of liquid to said surface of the soap, so that the liquid flows rapidly across said surface in a thin sheet moving substantially radially outwardly to dissolve soap from said surface; abruptly deflecting the moving sheet of liquid as it leaves the periphery of the soap to cause it to rebound back onto said surface to be recurrently circulated thereacross to increase the concentration of the soap solution and to entrain air in the solution to form a primary lather from the same when the solution reaches the proper concentration; and further agitating the primary lather so formed, in the presence of air, to produce lather of the desired consistency.

3. The method of producing lather which is characterized by the steps of: rotating a cake of soap at high speed with an exposed face thereof substantially perpendicular to the axis of rotation; admitting air directly to the exposed face of the soap cake; supplying liquid to said face of the soap to thus enable centrifugal force consequent to rotation of the soap to move the liquid radially outwardly across said face of the soap in a thin film in which quantities of soap dissolve to form a soap solution; abruptly deflecting the outwardly moving liquid as it leaves the soap to cause at least a portion thereof to be recurrently circulated across said face of the soap to increase the concentration of the soap solution and to entrain air therein so as to form a primary lather; and injecting additional liquid onto said face of the soap at a rate equal to the rate at which liquid having soap dissolved therein is converted into primary lather.
